(57) CLAIM

The ornamental design for a container with removable lid, as shown and described.

DESCRIPTION

FIG. 1 is a front view of the container with a removable lid showing my new design for a container with removable lid, the rear view being a mirror image thereof,

FIG. 2 is a right side view thereof, the left side view being a mirror image thereof,

FIG. 3 is a plan view thereof,

FIG. 4 is a bottom view thereof,

FIG. 5 is a front view of the container with lid removed and the clamp opened, the rear view being a mirror image thereof,

FIG. 6 is a front view of the lid with container removed, the rear view being a mirror image thereof,

FIG. 7 is an exploded front view of the container and lid, the rear view being a mirror image thereof; and,

FIG. 8 is a perspective view of the container and lid as shown in FIGS. 1 through 4.
